UNITED STATES PATENT OFFICE.

ALEXANDER WAYRICH, OF BROOKLYN, NEW YORK, ASSIGNOR TO UNDERWOOD TYPE-WRITER COMPANY, OF NEW YORK, N. Y., A CORPORATION OF DELAWARE.

EXHIBITION DEVICE.

1,218,231.

Specification of Letters Patent.

Patented Mar. 6, 1917.

Application filed February 5, 1914. Serial No. 816,695.

To all whom it may concern:

Be it known that I, ALEXANDER WAYRICH, a citizen of the United States, residing in Brooklyn borough, in the county of Kings, city and State of New York, have invented 5 certain new and useful Improvements in Exhibition Devices, of which the following is a specification.

This invention relates to display apparatus 10 adapted to present a panoramic series or succession of scenes, views, mechanical devices, machines for advertising purposes, etc.

In my co-pending application, Serial No. 795,891, disclosing illusionary apparatus by 15 means of which each of several living scenes or acts is caused to gradually fade away as the succeeding act is brought to view, the two acts appear contemporaneously and apparently in the same place during a period 20 of the transition, one view dissolving into the other.

An object of this invention is to provide a compact arrangement of compartments 25 containing merely objects to be displayed, whereby the apparatus can be placed in a store window or other display place, particularly in situations where room is limited. To further subserve this object, the invention provides means whereby a number of 30 objects of a series to be displayed, may be permanently located in one compartment and brought singly into view in alternation with other devices of the series in a second compartment.

The cabinet or other closure, to contain the articles or the like to be displayed, may 35 be divided into a front and rear compartment by a vertical partition, and the front compartment further divided by a horizontal partition into an upper dark chamber and a lower display section or compartment. Said dark chamber may be provided with an opening or window in front and a window in the vertical partition, through which 40 windows the spectator may view the apparatus, etc., placed on display in the rear compartment. Such apparatus is seen through a plate glass in the dark chamber, said glass extending in an inclined direction 45 across the dark chamber between the windows. The rear display compartment is lighted by a series of hidden electric lights which illuminate the apparatus on display in said compartment.

The lower front compartment also con-

tains apparatus or the like, adapted to be brought into view when lighted by a series of hidden lamps within the compartment, the reflection of said apparatus being seen in the plate glass which acts as a mirror, so 60 that said apparatus appears to the spectator to be in the rear compartment. The latter compartment alone is first lighted to display the apparatus therein. The lights of the rear compartment are then gradually 65 dimmed and the lower front compartment at the same time, gradually illuminated so that the apparatus therein comes into view in place of that in the rear compartment. During this period of transition, the objects 70 in both compartments may be seen apparently in the same position, one gradually merging into the other.

Either or both compartments may contain a plurality of devices adapted to be brought 75 singly and successively into position to be seen by the spectator. Said devices may be mounted on a rotatable carrier so that after one device thereon, has been displayed and darkened, and while a device in the other 80 compartment is illuminated, said carrier may be rotated to bring another device thereon into position for display, and when in said position, the compartment may again be gradually illuminated, and the lights in 85 the other compartment at the same time, gradually dimmed. In this way the scene changes to display first, an object in one compartment, and then an object in the second compartment, and then a third object 90 in the first compartment, etc., said objects all appearing to be in the same position.

Other features and advantages will hereinafter appear.

In the accompanying drawings,

Figure 1 is a sectional elevation view of an apparatus adapted to illustrate the development of the typewriter art.

Fig. 2 is a diagrammatic view of the electric-lighting circuits and apparatus.

Fig. 3 is a front elevation view of the apparatus displayed in a store window.

The cabinet or closure 1 adapted to contain the articles, machinery, apparatus, or other devices to be displayed, is divided by 105 a vertical partition 2 into a rear compartment 3 and a front compartment which in turn is divided by a horizontal partition 4 into an upper chamber or compartment 5 and a lower chamber 6. The compartment 110

5, which is kept comparatively dark and may be termed the dark room, is provided with a front opening or window 7, through which projects a frame or casing 8 forming 5 a passage-way of considerable depth, said casing having a flared front 9 connected to a vertical wall 10, forming the back of an ornamental front framework 11. The partition 2 is provided with a window 12 in 10 line with the window 7, and preferably, substantially the same size and shape as the window 7. Within the chamber 3 is a series of electric lamps 13 surrounding or partially surrounding the window 12 for illuminating the display articles in the chamber 3; said lamps being hidden from the view of the spectators by a shield 14 of opaque material.

The apparatus herein shown is designed 20 to illustrate the development of the typewriter art in three successive views or scenes, the first representing the method of writing, prior to the advent of the typewriting machine. For this purpose, a quill pen 15 appears 25 in an ink-well 16 on a writing-desk 17, this apparatus illuminated by the lamps 13 and seen by the spectators through the windows 7 and 12. A plate glass 18 extends diagonally from the upper to the lower wall 30 of the dark room 5 between the windows 7 and 12, but is invisible to the spectators.

Located in the dark room 5 and surrounding the window 12 is a frame 19 containing a bank of lamps 20 which illuminate with 35 a subdued light the front plate or wall 21 of said frame 19, said front plate being formed of ground glass or other translucent material. The walls 22 and 23 of the frame 19 are preferably opaque.

40 In the front display chamber 6 is located a typewriting machine 24, secured to a vertical wall or support 25 in such position that when a bank of lamps 26 are lighted, to illuminate the chamber 6, the machine 24 45 will be reflected in the plate glass 18 which forms a mirror, so that the machine 24 will appear to the spectator to be in the rear compartment 3 and standing in a normal horizontal position. The window 27 50 through which the machine 24 is viewed is preferably, substantially the same size as the window 12, and when seen reflected in the mirror appears to be in the same position as the window 12. The lamps 26 are hidden 55 from the view of the spectator by the opaque walls of the frame 28, containing said lamps.

To present the first view to the spectators, who are positioned in front of the 60 frame 11, the lamps 13 and 20 are lighted while the lamps 26 in the compartment 6 remain dark. The apparatus comprising the quill-pen, etc., are thus brilliantly lighted and seen through the glass 18, the latter being invisible. The lights 13 are now grad-

ually dimmed by means hereinafter described, and the lamps 26 in the chamber 6 at the same time, gradually lighted. The scene in the chamber 3 thus gradually fades from view, and at the same time, the machine 24 is gradually brought into view, being reflected in the mirror 18 and apparently located in the same position as the apparatus in the chamber 3. As the lights 26 increase in brilliancy, bringing the machine 24 70 clearly into view, the first apparatus disappears entirely. During this transition period the apparatus in both compartments are seen more or less distinctly, and at the same time apparently occupying the same 75 position.

It will be noted that the frame 19 is permanently lighted, and as it remains stationary and appears to the spectator as a frame surrounding the apparatus seen in the chamber 6 as well as that in the chamber 3, it aids in making the illusion more complete. The illuminated frame 19 further serves as a blinder to assist in preventing the spectators from seeing anything in 80 either of the display compartments, except when the latter are illuminated.

The typewriting machine 24 illustrates an old style, "blind" machine in which the types strike upward against the under side of the platen 24^a, the writing being invisible except when the carriage 24^b is lifted. Such machines were in vogue in the early days of 90 the typewriter art.

When the compartment 6 is fully lighted 100 and the compartment 3 darkened, a frame 29 to which the desk 17 and writing utensils thereon are secured, may be rotated with or about a shaft 30 on which said frame is mounted, to carry said utensils below the window 12 and bring into position for display a typewriting machine 31 secured to the opposite side of the frame 29. The lights 26 in the chamber 6 are now gradually dimmed, and the lamps 13 gradually 105 lighted so as to bring into view the up-to-date typewriting machine 31 which appears to take the place of the antiquated machine 24, as the latter gradually disappears from view. A weight 32 may be secured to the frame 29 opposite the machine 31 to counter-balance the latter, so that said frame and the parts carried thereby, will be substantially balanced in any position. The stops 33 and 34 in the path of a projection 110 35 limit the rotation of the frame 29 in both directions. The various parts carried on the frame 29 are securely attached thereto in any convenient manner so as to be retained in position when the frame is inverted.

The electric-lighting system is diagrammatically illustrated in Fig. 2. The lamps may be electrically connected through positive and negative mains 36 and 37, design- 125 130

nated + and —, respectively, to any suitable source of electric current supply. The bank of lamps 20 which illuminate the frame 19 is connected through a switch 38 to the mains 36 and 37. The bank of lamps 13 for illuminating the compartment 3 is connected in circuit with a rheostat or dimmer 39 by means of which the lamps may be gradually lighted and brought up to full 10 candle power or gradually dimmed and finally cut out of circuit. The circuit for the lamps 13 may be traced from the positive main 36 through one blade of the switch 40, through the conductor 41, lamps 15 13, conductor 42, resistance 39^a of the rheostat, arm 39^b of the rheostat, conductor 43 and switch 40, to the negative main 37. The bank of lamps 26 for illuminating the 20 chamber 6 are in series with a rheostat or dimmer 44 and may be connected through a switch 45^a to the mains.

In changing the scene from the chamber 3 to the chamber 6, both rheostat arms are moved at the same time, from left to right. 25 The resistance 39^a is thus gradually introduced into the circuit of the lamps 13 to dim them down and the resistance in the rheostat 44 is, at the same time, gradually cut out of the circuit for the lamps 26, so 30 that the latter are gradually lighted. To again change the scene to the compartment 3 this operation is reversed. A set of lamps 45 may be employed to illuminate the ornamental front or framework 11, and for 35 this purpose, the lamps 45 may be placed in inclosed portions 46 of the framework, and the front 47 may be either translucent or transparent. Such lamps tend to complete the illusion by making the articles displayed 40 appear by contrast in a much darker space. Ornamental curtains or drapery 48 may be supported in the framework 11 and surround the casing 8.

The apparatus as described is well adapted 45 to be placed in a store window for advertising purposes. As shown in Fig. 3, it is placed behind the plate glass 49 of a store window 50. The location of the chamber 6 below the dark chamber, effects 50 a material economy of space.

It will be understood that the typewriting machines and other display apparatus herein shown are merely illustrative of one of the numerous lines of apparatus, machinery, articles of manufacture, views, etc., which might be displayed in accordance with the principles of this invention.

Variations may be resorted to within the scope of the invention, and portions of the 60 improvements may be used without others.

Having thus described my invention, I claim:

1. In a display apparatus to be viewed from a distance, the combination with a 65 compartment comprising a window through

which the articles in said compartment may be viewed, of means in said compartment for positioning a number of articles in succession to be viewed through said window, a second compartment for display articles, 70 means for causing the articles in said second compartment to appear to be in the first-named compartment, means for alternately illuminating each of said compartments and dimming the other, and means 75 for providing illumination in front of the window.

2. In a display apparatus, the combination of a transparent reflector, a compartment behind said reflector, a plurality of 80 devices in said compartment to be displayed, means for moving said devices successively into position to be viewed through said reflector, an additional device in position to be reflected from said reflector so as to appear from the viewpoint to be in the display position of the first-named devices, means for lighting articles at both display positions, means to gradually increase the light for one position and reduce the light 90 for the other, and means for illuminating the space behind the reflector and in front of said compartment.

3. In a display apparatus, the combination with a plurality of display compartments, of a plurality of articles to be displayed in one compartment, means in said compartment to move one of said display articles out of display position and move another into display position, a transparent 100 reflector positioned to permit an article in one compartment to be reflected therein, and to permit an article in the other compartment to be seen therethrough, said articles appearing to the spectator to be substantially in the same position, illuminating means for said compartments comprising apparatus for gradually lighting one compartment and simultaneously reducing the light in the other compartment, and means 110 for illuminating the space behind the reflector in front of the compartment behind said reflector.

4. In a display apparatus, the combination of a rotary supporting device adapted 115 to bring a plurality of articles thereon successively into display position, means for supporting another article in a second display position, lighting apparatus for alternately lighting articles in said display positions, and means for causing each article when brought into view to appear substantially in the same position as the preceding article.

5. In a display apparatus, the combination of a rotary supporting device adapted 125 to bring a plurality of articles thereon successively into display position, means for supporting another article in a second display position, lighting apparatus for alter- 130

nately lighting articles in said display positions, and a transparent mirror in position to reflect the light from the articles in one of said display positions and cause it to appear to the spectator to be in the other display position.

6. In a display apparatus, the combination with a compartment having a window therein, of a support, said support rotatable about a horizontal axis, devices mounted on said support and brought alternately, by the rotation of said support, into position to be viewed through said window, a second compartment having a window therein, a transparent mirror positioned to permit articles in one compartment to be seen reflected therein, and articles in the other compartment to be seen therethrough, and means for alternately lighting said compartments.

7. In a display apparatus, the combination of a display compartment, a frame therein mounted to have a limited turn about a horizontal axis, to bring articles mounted on either side of said frame into display position, a second display compartment arranged at a right angle to the first compartment, a transparent screen extending diagonally between said compartments, means for lighting up objects in either compartment, means for making said lighting up gradual, and an open-ended casing opposite said transparent screen.

8. In a display apparatus, the combination of a display chamber, a support mounted for movement therein to bring display articles successively into horizontal position for display, a second chamber, means for mounting in said second chamber articles at right angles to the horizontal position of the articles in the first chamber, and a transparent reflecting plate mounted at an angle of forty-five degrees to each of said positions, means for illuminating or dimming articles in either of said chambers, the position of the articles in the second chamber being such that the article when reflected appears to occupy the position of an article when projected from the first mentioned chamber, a partition in front of the mirror, a window for observation through the partition, and controllable means for illuminating the front to complete the illusion produced by the illumination of the object in the first and second chambers.

9. The combination of a display compartment having a window therein through which the articles may be displayed, a rotary support mounted in said compartment for rotation into a plurality of display positions to bring display articles successively into position to be viewed through said window, and a second compartment having a window through which display articles may be viewed, lighting means for alter-

nately lighting said compartments, and means for causing the articles in both compartments to appear to the spectator to be in substantially the same position.

10. In a display apparatus, the combination of a closure comprising a vertical partition dividing it into front and rear compartments, and a horizontal partition dividing the front compartment into an upper chamber and a lower compartment, windows in said partitions, a diagonal transparent mirror in said upper chamber between said windows, means for alternately lighting said rear compartment and said lower compartment, a front window in said chamber through which light from said compartments may be transmitted, and means for illuminating the border of the window behind said mirror, the windows being placed symmetrically with respect to said screen, whereby the illuminated border of the rear window may be seen in border relation to the lower window when the lower chamber is lighted and the upper dark.

11. In a display apparatus for use in store windows, the combination of a closure of a size to be placed behind a window, and comprising display compartments and a dark chamber, of a front window in said dark chamber, windows connecting said chamber with said display compartments, means for alternately lighting said compartments, a transparent reflector in said dark chamber in position to transmit light from articles in one display compartment and reflect light from articles in the other display compartment so that said articles all appear to a spectator in front of the store window to be in substantially the same position, means for illuminating the border of one of said chamber windows, said windows being symmetrically placed with reference to the screen, whereby they may appear in superposed position, and means for illuminating the border of the front of the enclosure.

12. In a display apparatus, a cabinet having vertical and horizontal partitions dividing it into a darkened chamber and display compartments located respectively behind and beneath said chamber, windows in said partitions, a transparent mirror extending diagonally across the darkened chamber in position to transmit light from the rear display compartment and reflect light from the lower display compartment through a front opening or window in said chamber, an article placed on end in the compartment beneath said chamber, articles placed horizontally in the compartment behind said chamber, and a pivotal support for said last-named articles adapted to hold one in line with its window and the other below said window and behind said other compartment.

13. In a display apparatus, the combination of a cabinet comprising a darkened chamber and display compartments, means in one compartment for successively bringing into display position a number of articles or devices to be displayed, a transparent mirror in said darkened chamber positioned to transmit light from the articles in one compartment and reflect light from the articles in the other compartment to a common viewpoint, and means for partly illuminating said darkened chamber when an article is viewed by light transmitted through said mirror.
14. In a display apparatus, the combination with a front and means for illuminating said front, a chamber behind said front, a transparent mirror arranged in said chamber, two chambers arranged at right angles to each other in open communication with said transparent mirror in such a way that the transparent mirror is arranged at an angle of forty-five degrees between them, means for illuminating objects in the interior of each of said last mentioned chambers, a pivotally mounted support in one of said chambers, objects on said support adapted when said support is turned to occupy substantially identical position, and objects mounted in the second of last said chambers adapted to be seen by light reflected from said transparent screen and when so reflected to appear to occupy the position of the articles on the rotating support in the other screen, the light reflected from the rotating support passing directly through said transparent mirror.
15. In a display apparatus, the combination with a front and means for illuminating it, of a chamber behind said front, means for intermittently illuminating it, a compartment back of said chamber, pivotally mounted objects in said compartment adapted to be viewed alternately as swung on their common pivots, concealed means for intermittently illuminating said objects so that they are viewed by light reflected from their surfaces, a second compartment, a transparent mirror in said chamber through which said objects can be seen, an object in said second compartment adapted to be viewed by reflection from said mirror, and concealed means for lighting said second compartment.
16. In a display apparatus, the combination with a front and means for illuminating it, of a chamber behind said front, means for intermittently illuminating it, a compartment back of said chamber, pivotally mounted objects in said compartment adapted to be viewed alternately as swung on their common pivots, concealed means for intermittently illuminating said objects so that they are viewed by light reflected from their surfaces, a second compartment beneath said chamber and in front of said first compartment, a transparent mirror in said chamber through which said objects can be seen, an object in said second compartment adapted to be viewed by reflection from said mirror, and concealed means for lighting said second compartment.
17. Illusion apparatus comprising a cabinet having a front opening, a front chamber containing an inclined plate adapted to reflect and transmit light rays, a chamber to the rear of said plate for containing an object visible at the said cabinet opening through said plate, a chamber opposite the face of said plate for containing an object that is reflected by the plate to be visible at the front opening, lighting means whereby said two object chambers can be alternately illuminated, and means adapted to constantly illuminate the walls of said front chamber.
18. In a display apparatus, the combination with a dark chamber, a display compartment behind said chamber, a second display compartment arranged laterally with reference to said chamber, a bordered opening from said chamber to each compartment, an inclined transparent mirror in said chamber between said openings, means for lighting both of said compartments at will and means for continuously illuminating the border of the opening behind the mirror the two openings being so arranged that they are substantially equidistant from the mirror, whereby the transmitted light from the illuminated border may be seen superposed in border relation to the reflected light from the other opening.

ALEXANDER WAYRICH.
